UNITED STATES PATENT OFFICE.

ABEDNEGO DEWES, OF NEW YORK, N. Y.

EYELETING-MACHINE.

SPECIFICATION forming part of Letters Patent No. 760,617, dated May 24, 1904.

Application filed September 19, 1903. Serial No. 173,817. (No model.)

To all whom it may concern:

Be it known that I, ABEDNEGO DEWES, a citizen of the United States, and a resident of New York, county and State of New York, have invented Improvements in Eyeleting-Machines, of which the following is a specification.

The improvements in eyeleting-machines forming the subject of this invention embrace in one machine a means for puncturing or forming the holes in the material to be eyeleted for the reception of the eyelets, means for applying the eyelet to the hole so formed, and means for moving the material after being punctured to bring the puncture or hole formed therein into position to receive the eyelet, the puncturing and eyeleting means being stationary and preferably arranged side by side.

It also includes improvements in the eyelet-applying device whereby both the eyelet feeding and upsetting mandrels are moved toward the material, so that the eyelets will be clenched thereon without disturbing the material, and improved operating devices for actuating the puncturing, the eyeleting, and the material-carrying means whereby they act in unison and perform their functions during one complete operation or revolution of the machine.

These improvements, with others relating to special features of construction, will now be fully described, reference being had to the accompanying drawings, in which—

Figure 1 is a side elevation of a machine embodying my improvements. Fig. 2 is a part plan view of the same. Fig. 3 is a rear elevation. Figs. 4 and 4^a are views looking toward the left-hand sides of the eyeleting and the puncturing cams, respectively; and Fig. 5 shows a portion of the automatic clutch of the machine.

The material or article to be eyeleted, which will generally be in sheet form, is placed upon the table *a* and held thereon by the holding-guides *a'* and *a''*, having spring-clamps and secured adjustably on the table by slot and clamping-screw and nut connections and which are suitably set to retain the material or article in proper position to be acted upon

by the puncturing or punching device when the table is in its normal position. These spring-clamps are shown as extensions *a'* *a''*, projecting from the faces of the adjustable parts *a'* *a''*. This table *a* is adapted to slide or move laterally, and to enable it to be moved with freedom it is preferably carried by parallel links or arms *b* *b*, which are pivotally connected to the under side of the table at their upper ends and are connected to shafts *b'* and *b''*, having bearings on the bed *c* of the machine. The shaft *b''* extends to the rear of the machine and is there provided with arm *d*, having a roller *d'* at its end which is acted upon by the face-cam *e*, secured to the main shaft *f*, which is fitted to rotate in bearings located at the rear of the bed *c*. The table-controlling device is provided with means by which the table may be set and held in its initial position, here shown as consisting of an arm *g*, secured to the shaft *b'* and having a set-screw *g'* passing through its end and arranged to bear on the bed *c*, and a spring *g''*, connected between a moving part of the table-controlling device and a fixed point on the machine, arranged to bring the table into its normal or initial position after having been moved by the cam *e*.

The punching device *h* is of the ordinary construction. Its body or main portion and the body or main portion *i* of the eyeleting device are for convenience and cheapness of manufacture combined in one casting in the form of a standard *j*, which is rigidly secured to the bed *c*. The punch *h'* is actuated by the lever *h'*, which has a link *h''* connected at its rear end. This link extends downwardly, and its lower part is slotted, so as to embrace, be controlled by, and slide over the shaft *f*. The lower or eyelet-feeding mandrel *i'* of the eyeleting device is actuated by the lever *i'*, which is pivoted to the standard *j* at *i''* and has a pendent link *i''*, also fitted to slide on the shaft *f* by means of a guide-slot formed in its lower part and which embraces the said shaft. This lever *i'* through the medium of the link *i''* causes the eyelet to be fed from the eyelet-reservoir *i''* to the eyelet-setting device. So far this part of the eyeleting device is of the ordinary construction. To provide for the

non-disturbance of the material which the eyelet is being applied thereto, the upper or upsetting mandrel j' is fitted to slide in the body i and is actuated from the lever i' by the link j^2 and the side lever j^3 , pivoted at j^4 to the side of the standard j and having its outer end working in a slot or groove in the mandrel j' , the link j^2 being connected to the inner end of the lever j^3 and to the lever i' , as shown at Fig. 1, the arrangement being such that as the eyelet-feeding mandrel i' rises after taking an eyelet from the chute of the eyelet-box and passes the eyelet through the hole made in the material the upsetting-mandrel j' is caused to descend, and the eyelet is clenched between the two mandrels onto the material while it rests normally on the table a .

On the shaft f is fitted two face-cams k and l , between which the two links h^2 and i^2 play. Both of these cams are fitted to rotate positively with the shaft f , but are adapted to be set on said shaft in two positions for the purpose hereinafter described, which may be accomplished by the feather f' and slot connections and set-screws f'' . (Shown in the drawings.) The cam k has a cam-groove k' in its face adjacent to the link h^2 and into which extends the roller m on the link h^2 when the cam is set to operate the punching device h , and the cam l has a cam-groove l' in its face adjacent to the link i^2 of the eyeleting device and into which extends the roller n on the link i^2 when the cam is set to operate the eyeleting device. The links h^2 and i^2 are also provided with rollers o and p , fitted on bracket extensions o' and p' of the links h^2 and i^2 . These rollers o and p are adapted to roll in circular grooves k^2 and l^2 of the cams k and l , respectively, but are just clear of the cams when said cams are set to operate both the punching and eyeleting devices, as shown at Fig. 3.

The machine, as before stated, performs one complete operation—that is, the punching device is first operated, then the table is moved, and then the eyeleting device is operating—for one complete movement or revolution of the machine, and to cause such action it is advisable to use an automatic stop device, which may be of any of the usual forms. A suitable device for such purpose is here shown consisting of a pulley q , which will be continuously driven, a sliding clutch member r on its hub, a clutch member s , secured to the shaft f , and a setting and releasing arm t , the action being such that with the arm t between the clutch members r and s said members are separated and no motion imparted to the shaft f . Now upon the arm t being depressed and immediately released the clutch members come together and the shaft f is rotated; but before it has made a complete revolution the arm t moves up between the members and by the wedge-piece on the member s forces the members apart,

causing a disengagement of the clutch and a stoppage of the machine.

As before stated, this machine is designed to be used as an individual punching-machine and as an individual eyeleting-machine as well as a compound punching and eyeleting machine. If it is desired to perform punching operations only, the cam l is slid on the shaft f until the roller p enters the circular groove l^2 and the roller n leaves the groove l' , said rollers being so arranged that before the roller n leaves the cam the roller p will be engaged, so that the eyelet mechanism is always controlled and the eyeleting-mandrels are held in inoperative positions when the machine is used for punching purposes only. If eyeleting operations only are to be conducted, then the cam k is slid on the shaft f to change it from its operating to its locking roller in the same manner as the cam l is changed. Under both of these modes of operation it is desirable that the table a be held stationary. This may be accomplished by screwing the set-screw g' sufficiently far through the controlling-arm g to set the roller d' away from the cam e out of the range of action of said cam.

I claim as my invention—

1. In an eyeleting-machine, the combination with a puncturing device and an eyeleting device, arranged side by side and permanently located, of a table forming the sole support for the material to be eyeleted and provided with adjustable holding devices adapted to hold and locate the material to be operated upon; and means for moving the table so as to bring the hole produced by the puncturing device into the field of action of the eyeleting device.

2. In an eyeleting-machine, the combination with a puncturing device and an eyeleting device, arranged side by side and permanently located, of a table forming the sole support for the material to be eyeleted and provided with adjustable holding devices adapted to hold the material to be operated upon, means for moving the table so as to bring the hole produced by the puncturing device into the field of action of the eyeleting device; and means for setting the table out of action of its operating means and for adjusting the extent of its movement.

3. In an eyeleting-machine, the combination with a puncturing device and an eyeleting device, arranged side by side and permanently located, of a table adapted to hold the material to be operated upon and to move so as to bring the hole produced by the puncturing device into the field of action of the eyeleting device, said table being carried by parallel rocking arms; and means for rocking the arms.

4. In an eyeleting-machine, the combination with a puncturing device and an eyeleting device, arranged side by side and permanently located, of a table forming the sole support

for the material to be eyeleted and provided with guides adapted to hold the material; means for actuating the puncturing device; means for actuating the eyeleting device; and means for controlling the table to move it from its normal position during the puncturing operation into position to bring the puncture made in the material into the field of action of the eyeleting device; and means for moving the table back into its normal position.

5. An eyeleting - machine, comprising a puncturing device, an eyeleting device, a movable table adapted to carry the material to be operated on and a main driven shaft, in combination with a cam fitted on the shaft and adapted to be set in different positions longitudinally thereon and having an operating-groove and a circular groove; a lever-and-link connection between the puncturing device and 15 the cam provided with a roller for each of the cam-grooves, means whereby the cam may be so adjusted on the shaft that only one of the rollers at a time is in operative connection with its groove.

25 6. An eyeleting - machine, comprising, a puncturing device, an eyeleting device, a movable table adapted to carry the material to be operated on, and a main driven shaft, in combination with a cam having an operating-groove and a circular groove and fitted on the 30 shaft so as to be set to occupy different longitudinal positions thereon; a lever-and-link connection between the eyeleting device and this cam, and provided with a roller for each 35 of the grooves of this cam, means whereby this cam may be so adjusted on the shaft that when one roller is in operative position with its groove the other one is out of contact with its groove.

7. An eyeleting - machine, comprising a 40 puncturing device, an eyeleting device, a movable table adapted to carry the material to be operated on, and a main driven shaft, in combination with parallel rocking arms connecting the table to the bed of the machine, an 45 arm connected to the rocking axis of one of the parallel rocking arms; a cam on the driven main shaft arranged to actuate this arm; a retractile spring arranged to act in opposition to the actuating-cam; and an adjustable stop 50 for governing the movement of the table; means for actuating the puncturing device; and means for actuating the eyeleting device.

8. An eyeleting - machine, comprising a 55 puncturing device, an eyeleting device, a movable table adapted to carry the material to be operated on, and a main driven shaft, in combination with a cam fitted on the shaft and adapted to be set in different positions longitudinally thereon and having an operating-groove and a circular groove; a lever-and-link connection between the puncturing device and the cam provided with a roller for each of the cam-grooves, means whereby this cam may be so adjusted on the shaft that only one of them 60 at a time is in operative connection with its groove, the positions of the cam-grooves and the rollers being so related that as the cam is longitudinally moved the free roller will be engaged by its groove before the other roller 65 is entirely clear of its groove.

In testimony whereof I have hereunto subscribed my name this 16th day of September, 1903.
